UNITED STATES PATENT OFFICE.

SAMUEL A. HARRISON, OF BROOKLYN, NEW YORK.

ORIENTAL TYPE-WRITER.

977,448.

Specification of Letters Patent. Patented Dec. 6, 1910.

Application filed December 15, 1909. Serial No. 533,132.

To all whom it may concern:

Be it known that I, SAMUEL A. HARRISON, a citizen of the United States, residing in Brooklyn, in the county of Kings and State 5 of New York, have invented certain new and useful Improvements in Oriental Type-Writers, of which the following is a specification.

This invention has for its object to provide 10 a typewriting machine in which the relative movement of the platen or paper support, and of the typebar or member carrying the type that print on the paper on the platen will be effected by intermittent advances in one direction by a certain adjustment, and by certain different adjustment the same operating device will cause the relative advancement of the two members to be reversed whereby the feed of the 20 member that is advanced is in the opposite direction. By this means the typebar or type-carrying mechanism can carry two or more different alphabets, one of which such as the English is printed from left to right 25 on the paper, while as a result of said adjustment and shifting of the typebar to bring another alphabet to operative position, the printing will read in the reverse direction from right to left; as for instance the 30 Hebrew language.

In the accompanying drawing illustrating 35 one embodiment of my invention Figure 1 is a side elevation. Fig. 2 is a plan view. Fig. 3 is a section on the line 3—3 of Fig. 2. Fig. 4 shows enlarged a fragment of the index bar. Fig. 5 shows enlarged a fragment of the multiple type bar. Fig. 6 is a section on the line 6—6 of Fig. 2. Fig. 7 is an end elevation enlarged of the advance 40 mechanism. Fig. 8 is an end view of the part shown in Fig. 7. Fig. 9 is a fragmentary view of the actuating dogs shown in Fig. 7 but in the reverse position.

The device is shown as comprising a suitable base B having mounted thereon a standard 45 2 carrying a head 3. On opposite sides of the head are hinge portions 4 and 5 in which swing arms 6 and 7 rigidly secured to the typebar cradle 8. A carriage denoted 50 generally by 9 reciprocates in a guideway 10 on the base in a path extending at right angles to the axis of the cradle 8 as indicated in Fig. 2. This carriage has bearings 11 and 12 at its respective ends in which 55 swings the roller or platen 13 for carrying

the paper to be engaged by the typebar 14 that turns in bearings 15 and 15^x in the ends of the cradle 8. The cradle has an opening 16 in its bottom at the middle portion into which opening projects the type 17 on the 60 typebar, when the arms and cradle are swung downward to engage the platen or sheet thereon. The typebar is shown as having three sets of alphabets 17, 18 and 19, the set 18 being the English language, 17 the 65 Hebrew language and 19 may be the upper case English.

An index bar 20 is mounted to turn in lugs 21 and 22 on a plate 23 carried by the head 3 which plate is shown provided with notches 24 each registering with a character on the index bar. These characters are spaced on the index bar corresponding to the type on the typebar 17. The typebar turns in lugs 25 and 26 at the ends of a plate 27 whose opposite edges slide in slots 29 and 30 in the cradle 8. A suitable handle 31 is secured to the plate 27 and carries an index 32 arranged to register with and enter one of the notches 24 in the plate 23 on the 80 head of the frame. When this typebar is shifted under the cradle to register with the notch corresponding to any desired character, the same character on the typebar 17 will, from this endwise movement of the 85 typebar, be brought to position to engage the platen or sheet thereon, upon the typebar frame being swung downward. The index bar 20 carries the same alphabets as arranged on the typebar and spaced the same 90 distance apart. When the typebar is turned to bring different alphabets at the bottom, the index bar is similarly turned to bring the same alphabet into position adjacent the notches to be observed by the operator when 95 he shifts the typebar endwise to bring the pointer 32 opposite the desired letter. The same handle is used for swinging the typebar frame downward and the index will thereupon enter the notch that will serve to, 100 properly position the typebar endwise to cause the type to be accurately positioned for engagement with the paper on the platen. A spring 33 on the plate 27 engages the flat faces of the typebar adjacent the several alphabets to accurately position the type when the bar is turned whereby the type will be properly presented at the opening for engaging the platen. Also a spring 34 on the plate 23 engages flat faces on the in- 110

2 dex bar 20 to cause it to be held in adjusted positions. A suitable spring 35 on the standard 2 engages the arm 7 to normally retain the swinging cradle with the typebar in the elevated position and returns it when depressed. The arm may have a lug 36 engaging the head to limit the upward swing effected by the spring 35.

The platen 18 is provided with any suitable paper retaining device such as a spring plate 37 for pressing the paper against the platen, and it may be turned by a head 38 to line space the sheet. Any suitable means may be also provided for turning the platen such as a lever 39 carrying a dog 40 that will engage suitable teeth in the platen spindle to advance the platen a unit distance to write a new line. The platen is shown as provided with a cutting blade 40 pivoted at one end 41 of the platen with the other end normally locked by a pin 42 to press the paper against the platen. When desired the paper can be pressed against this blade and the part printed upon can be severed. The plate can be swung outward on its pivot 41 by removing the pin 42 to remove the paper or for other reasons.

Means are provided for intermittently advancing the platen to produce the proper letter space or word space between each depression of the typebar to effect the printing of a character. This intermittent advancing movement is effected by the operation of a suitable lever through connecting means, which connecting means in one position of adjustment will advance the platen at each operation of the lever in one direction; and upon adjustment of the said connecting means the same operation of the lever will result in the intermittent advancement of the platen the same unit distance, but in the opposite direction, by which means the platen can at will be fed to print from left to right, or from right to left. And this adjustment or change is effected by merely shifting a single lever or member. In the construction illustrated an operating lever 42 is pivoted on the base at 43, and has hinged thereto an arm 44 carrying a double pawl 45 pivoted thereon. This pawl has teeth 46 and 47 that respectively register with or engage rack bars 48 and 49 mounted on the base B, the arm 44 being drawn downward to cause such engagement of the pawls by spring 50 between the arm and the operating lever 42. When the pawl 45 is in the position indicated in Fig. 8, its tooth 46 will engage with the rack bar 48. Upon depression of the lever 42 the arm 44 will be advanced and the tooth 46 will ride over the ratchet teeth on the bar 48. Upon release of the lever the reaction of the spring 50 that was extended will cause the lever to be elevated and the arm 44 retracted. The pawl 46 will now engage the ratchet tooth

and shift the carriage and platen a unit distance, which is limited by suitable stops for the operating lever. But upon shifting the double pawl 45 from the position of Fig. 8 to that of Fig. 9, the pawl 46 will be thrown out of position for engagement with its rack bar and the other pawl 47 will be swung to position for engagement with its rack bar 49. Upon now depressing the lever 42, the pawl 47 being advanced by the arm 44 will positively actuate the rack bar that is mounted on the carriage to actuate the carriage a unit distance. And when the lever is released and elevated and the arm 44 retracted, this pawl 47 will ride free over the rack bar. Comparing this operation with the previous operation described with reference to the parts adjusted as shown in Fig. 7, it will be seen that the rack bar is advanced when the arm 44 moves in the opposite direction to that in which the arm 44 moves to advance the rack bar 48. Therefore with this adjustment the carriage will be intermittently advanced in the opposite direction, and this reversal of carriage movement is effected by the same movement or operation of the actuating lever 42, being caused merely by the swinging of the double pawl member, without any other adjustment or shifting of parts. A lever 53 is shown pivoted on the arm 44 and connected by link 54 with an eye 55 on the double pawl 45, whereby the swinging of this lever 53 will shift the double pawl to the positions of operation as just explained. When it is desired to release the carriage from the actuating ratchets, the arm 44 is simply elevated when the carriage can be moved freely in both directions.

Each time the lever 42 is depressed the carriage will be spaced for one character, but means are shown for causing the operation of this lever by the depression of the typebar to effect the printing operation. This is done by an arm 57 depending from the cradle 8 that engages the arm 42. The pin 58 is engaged by the extremity of the arm 42 to limit its depressing movement. And the upward movement of the arm 42 is limited by the upward swing of the typebar cradle and frame through the arm 57.

A bell 60 is provided on the frame and a swinging hammer 61 engages the bell when tripped. An arm 62 on the hammer 61 is engaged by the bent end 63 of a bar fast to the carriage.

Having thus described my invention, I claim:

1. In a typewriter, the combination of a frame, a carriage slidable on the frame, a rack bar on one of said two members, a double pawl member on the other of said two members, an operating lever for the carriage connected with the pawl, the double pawl member being shiftable whereby in

one position the operation of the lever will advance the carriage in one direction, and when the double pawl member is shifted in another position the same operation of the 5 operating lever will advance the carriage in the opposite direction.

2. In a typewriter, the combination with a frame, a carriage slideable on the frame, a rack member on the carriage, a double pawl 10 member arranged to engage the rack and advance the carriage, an operating member connected with the pawl for actuating it to advance the carriage, the pawl member being shiftable whereby in one position the 15 operation of said member will cause the pawl to advance the carriage in one direction, and when the pawl member is shifted to another position the same operation of the operating member will cause the pawl 20 to advance the carriage in the opposite direction.

3. In a typewriter, the combination with a frame, of a carriage slideable thereon, an 25 operating lever for the carriage, an arm pivoted to the operating lever, a double pawl member on the arm, a rack member on the carriage engaged by the double pawl member to advance the carriage upon swinging of the operating lever, the double pawl 30 member being shiftable whereby in one position the operation of the lever will advance the carriage in one direction, and when the double pawl member is shifted to another position the same operation of the 35 operating lever will advance the carriage in the opposite direction.

4. In a typewriter, the combination with a frame, of a carriage slideable thereon, an operating lever for the carriage, an arm 40 pivoted to the operating lever, a double pawl member on the arm, a rack member on the carriage engaged by the double pawl member to advance the carriage upon swinging of the operating lever, the double pawl 45 member being shiftable whereby in one position the operation of the lever will advance the carriage in one direction, and when the double pawl member is shifted to another position the same operation of the 50 operating lever will advance the carriage in the opposite direction, a swinging lever connected with the double pawl member and arranged to shift it to said positions of operation whereby the direction of movement of 55 the carriage can be reversed.

5. In a typewriter, the combination with a frame, of a carriage slideable thereon, an operating lever for the carriage, an arm pivoted to the operating lever, a double 60 pawl member on the arm, a rack member on

the carriage engaged by the double pawl member to advance the carriage upon swinging of the operating lever, the double pawl member being shiftable whereby in one position the operation of the lever will advance 65 the carriage in one direction, and when the double pawl member is shifted to another position the same operation of the operating lever will advance the carriage in the opposite direction, and a spring connected with 70 the operating lever and arm to return them to normal positions after being swung.

6. In a typewriter, the combination of a frame, a carriage mounted to slide on the frame, a lever pivoted on the frame, an 75 arm pivoted to the lever, a double pawl member carried by the arm to shift a pair of adjacent rack bars on the carriage having their teeth beveled respectively in opposite directions, the double pawl member having its engaging portions in different planes for engagement with the two rack members 80 respectively and arranged whereby in one position of the member one pawl will co-operate with its rack while the other pawl is 85 out of engaging position, causing advancement of the carriage in one direction by operation of the said lever, and when the double pawl member is shifted to another position one pawl will be shifted out of engaging position and the other pawl shifted into position for engagement with its rack, causing advancement of the carriage 90 in the opposite direction from the same operation of the lever. 95

7. In a typewriter, the combination of a frame, a carriage mounted to slide on the frame, a lever pivoted on the frame, an arm pivoted to the lever, a double pawl member carried by the arm to shift, a pair of adjacent rack bars on the carriage having their teeth beveled in opposite directions respectively, the double pawl member having its 100 engaging portions in different planes for engagement with the two rack members respectively and located whereby in one position of the member one pawl will co-operate with its rack while the other pawl is out of engaging position, and when the double 105 pawl member is shifted one pawl will be shifted out of engaging position and the other pawl shifted into position for engagement with its rack, a lever pivoted on the arm and connected with the pawl member 110 to shift it to its two positions of engagement 115 with the respective racks.
